CLAIM

The ornamental design for a headset for wireless telephone as shown and described.

DESCRIPTION

FIG. 1 is a front view of the headset for wireless telephone. FIG. 2 is a top view of FIG. 1 thereof.

FIG. 3 is a bottom view of FIG. 1 thereof.

FIG. 4 is a right side view of FIG. 1 thereof; and,

FIG. 5 is a front perspective of FIG. 1 thereof.

The broken lines in the drawings depict portions of the article that form no part of the claimed design. Boundary lines define spaces which form no part of the claimed design.
